PROCESS FOR THE MANUFACTURE OF
VELVET OR PILE ARTICLESRoger Motte, Roubaix, France, assignor to Societe
Anonyme Etablissements Motte-Bossut Fils,
Roubaix (Nord), FranceApplication October 1, 1934, Serial No. 746,433
In France October 27, 1933

2 Claims. (Cl. 139—392)

The present invention has for its object a process for the manufacture of velvet or pile articles allowing of obtaining several pieces in a single weaving operation, by avoiding any waste 5 and loss of yarn.

This process is substantially characterized by the fact that several ground textures and a single covering are simultaneously woven, the interlacing or binding being effected in such a manner 10 that, when the covering threads are cut, a portion of this covering is integral with each ground texture, thus producing several pieces of fancy velvet. For instance, in the case of two ground textures, the portions covered with pile on one of 15 said textures are complementary to those without pile of the other texture.

The invention is applicable as well to warp pile fabrics as to weft pile fabrics, but its application is particularly advantageous for weft pile fabrics.

20 A description will first be given in order to show how the invention can be carried into practice in the case of weft pile fabrics.

The distribution of the pile is effected on several ground textures simultaneously woven according to the distribution, on one or the other of these textures, of the binding points of the pile loops. 25

The cutting being subsequently effected by the usual methods, the separation of the ground textures determines as many fabrics variously covered with pile, and of covering complementary to each other.

30 Fig. 1 of the accompanying diagrammatic drawing illustrates, by way of example, a double cloth the weave of which is shown in Fig. 2. In this Fig. 2 the X's designate the threads "taken up" and the dots the threads which are "left".

Fig. 1 is a cross section, that is to say at right angles to the warp threads, which are indicated 35 at c¹, c². The weft threads 5, 1, 6, 2 form with these warp threads two ground textures T¹, T². The covering threads 3, 4, sometimes interlace or bind with both textures, as at l, and sometimes only take up the texture T¹, as at s.

40 45 After cutting the covering threads, two pieces of openwork pile P¹, P² (Fig. 3) are obtained, which carry pile at places complementary to each other, that is to say the portions covered with pile of one piece correspond to the apertures of the other.

50 As particular design which may be obtained, the loops u of P¹ can form a check pattern, and the loops v of P² another check pattern (Fig. 4), the apertures of one piece corresponding to the solid portions of the other.

Fig. 5 is a view similar to Fig. 1 showing the section of a fabric composed of three ground textures T¹, T², T³, giving, after separation, three openwork pile fabrics.

The new process presents, in the case of weft pile fabric, the following essential advantages:

(1) It allows of obtaining pile fabrics having an openwork covering, without loss of weft pile material.

(2) It allows of obtaining a fancy fabric identical to that produced by weaving in one piece with an important reduction in the number of picks per inch and varying according as weaving is effected with one or two supplementary textures, and also according to the proportion of the 10 picks to the ground and pile threads used in the 15 fabric.

(3) It allows simultaneous cutting of two or three pieces.

The process according to the invention is also 20 applicable to double piece velveteen. This double fabric is constituted by two ground textures between which the pile element works, this latter being herein constituted by a supplementary weft.

25 The application of this new process to this mode of weaving is effected by adding a supplementary texture to the under texture or to the top texture, or both to the under and top textures. The fancy effect is obtained after separation of 30 the ground textures and of the supplementary texture, the pile loops which it is desired to remove from the ground texture being bound on the threads of the supplementary texture, which itself forms, with these loops removed, a pile fabric 35 having an openwork covering, complementary to that of the ground texture.

A description will now be given, indicating how 40 the invention can be carried into practice in the case of warp pile fabrics.

With simple piece warp velvet, the cutting of which is effected on the weaving loom by removing from the fabric the wires inserted under the warp pile threads, the application of the process is effected by adding a supplementary texture on 45 the back of the ground texture, the loops which it is desired to remove from the ground texture binding on the picks of the supplementary texture, and, after separation of these two ground and supplementary textures, two complementary 50 covering textures are obtained.

In double piece warp pile fabrics, the openwork effects produced up to this day are obtained by momentarily interrupting the work of the pile threads between the under and top textures and 55

by causing these threads to work, either in the ground texture, or by allowing them to extend at the back of the under texture.

These methods of procedure complicate the manufacture and cause waste of threads.

The process according to the invention is applicable to double piece warp pile fabrics, by adding a supplementary texture under the lower texture, or on the upper texture, or both to the lower and upper textures, according as it is desired to obtain two or four openwork pile fabrics.

The fancy effect is obtained by binding, on the weft threads of the supplementary texture, the base of the loops it is desired to remove from the ground texture.

To the two ground textures T^1 , T^2 which are ordinarily obtained, is added a texture T^3 .

Some of the warp threads form ground textures. The others c are intended to constitute the covering and they alternately interlace or bind with two or three textures.

After cutting, a portion of these threads is integral with T^1 , another portion with T^2 and the remainder with T^3 , as illustrated in Fig. 7, this giving three pieces P^1 , P^2 , P^3 .

The new process presents, in its application to double piece warp pile fabrics, the following advantages:

(1) The threads forming the pile having approximately the same shrinkage or contraction, the weaving of this openwork velvet can be effected by unwinding the said threads from one and the same beam, instead of necessitating several warps, or their unwinding from bobbins arranged in a creel behind the weaving loom.

(2) It allows of doubling the production of this openwork velvet owing to the fact that the idle passage of the pile threads is used herein for covering the supplementary texture.

40 The new process is applicable to all weaves used, whatever may be the weave of the ground

texture which is employed (linen, serge, satin, etc.), the number of pile picks and threads relatively to the ground picks and threads, the length of the weft pile loops and the spacing apart of the two textures made of double piece warp pile, whether a ribbed, plain, woven, unbleached or dyed velvet is under consideration, and whether the binding of the pile loops is simple (V binding) or unremovable (W binding).

5 The above arrangements are given by way of example only; the forms, dimensions, materials used and all detail arrangements can be modified without departing thereby from the scope of the invention.

10 What I claim as my invention and desire to secure by Letters Patent is:—

1. A method for the manufacture of velvet, in which the pile element is formed by a supplementary weft, comprising the following steps: weaving a plurality of closely superposed base fabrics; interweaving pile threads at certain areas with the lowermost base fabric; passing the pile threads from said areas through the upper base fabric without interweaving therewith; looping the pile threads over a portion of the upper face of the upper base fabric; interweaving the pile threads with the upper base fabric to anchor the same therein; repeating the steps enumerated in any desired order; cutting the loops to form pile ends; and separating the base fabrics whereby patterned pile effects are produced on each of the base fabrics.

20 25 30 35 40 45 50 55 60 65 70 75 80 85 90 95 100

2. The method as claimed in claim 1 in which an intermediate fabric is woven and in certain areas the pile threads are passed through but two base fabrics being interwoven with the second only while in other areas they are passed through two of said fabrics without interweaving and are interwoven with the bottom fabric.

ROGER MOTTE.
